UNITED STATES PATENT OFFICE.

ADOLPH FRANZEN, OF NEAR HOWARD, SOUTH DAKOTA.

AUTOMATIC RAILWAY-CROSSING SIGNAL.

Application filed June 29, 1927. Serial No. 202,299.

This invention relates to new and useful improvements in automatic railway crossing signals and has for its object to provide a device of this character for warning pedestrians and occupants of vehicles of an approaching train.

A further object of my invention is to provide a signal of the character specified which is operated by suitable actuating means carried by the engine.

A still further object of my invention is to provide a crossing signal which may be operated by the engine a suitable distance from the crossing to give ample warning to 15 pedestrians and others.

With the foregoing and other objects in view that will appear as the nature of my invention is better understood, the same consists in the novel features of construction 20 illustrated in the accompanying drawings and more particularly pointed out in the appended claims.

Figure 1 is a side elevation of my automatic railway crossing signal, with the signal arm in retracted or inoperative position.

Figure 2 is a similar view, partly in section, with the signal arm in operative or signalling position.

Figure 3 is an inner face view of the upright support and the trip arms.

Figure 4 is a diagrammatic view, showing the upright support, trip arms and signal actuating means.

Figure 5 is a horizontal section, taken on line 5—5 of Figure 1 and Figure 6 is a detail sectional view.

Referring to the drawings for a more particular description of my invention and in 40 which drawings like parts are designated by like reference characters throughout the several views, my improved crossing signal comprises the upright support 1 which is mounted at one side of and parallel with the track and may be of any suitable length.

In actual practice, a signal is mounted at 45 each side of the track at the crossing in order that warning may be given of a train approaching in either direction, but since both signals are exactly identical in construction and operation, for the sake of convenience, I have shown and will describe but one signal.

An inverted L-shaped casing 2 is mounted 55 in an upright position on the outer wall of the support 1 and in the upper horizontal

shorter leg 3 of this casing is slidably mounted the signal arm 4 bearing the word "Stop". Signal arm 4 is connected with the upper end of a vertically disposed actuating lever 5 by the horizontal connecting link 6. The actuating lever 5 is pivoted intermediate its ends, as at 7, in the longer upright leg 8 of the inverted L-shaped casing 2 and has a slotted connection at its 60 lower end, as at 9, with the upper end of the bar 10 also pivotally mounted intermediate its ends, as at 11, in the longer leg of the casing. A similar bar 13 is pivotally mounted, as at 14, in a casing 15 mounted in an upper 65 position on the outer wall of the support 1 at the end thereof opposite the signal arm 4. The bars 10 and 13 are connected together at their upper and lower ends by the parallel wires 15' and 16 which work 70 over suitable guide rollers 17 journaled in suitable casings 18 secured to the outer wall or face of support 1.

The bars 10 and 13 are provided with the trip arms 19 and 20 which are located adjacent the inner wall or face of the support 1. In practice, when a train approaches the crossing in either direction, the signal actuating means 21 engages the trip arm 20 of the corresponding signal and causes said arm 85 to swing from a normal substantially upright position into lowered position, which operation through the medium of the connections described, throws the signal arm 4 into operative or signalling position and accordingly warns pedestrians and others of the approaching train. When the train reaches the crossing, the trip arm 19 is engaged and actuated to restore the signal arm 90 and other parts in normal or initial position. 95

From the foregoing description taken in connection with the drawings, it is thought that the construction, operation and advantages of my invention will be readily understood without requiring a more extended explanation.

Having described my invention, what I claim as new and desire to secure by Letters Patent, is:

1. An automatic railway crossing signal 105 comprising a support, a signal arm slidably mounted thereon and means for moving the latter into operative or signalling position when the train reaches a predetermined distance from the crossing, said means comprising a trip arm, and actuating lever pivoted to the support, a link between one end of said

lever and the signal arm and a flexible connection between the other end of the actuating lever and the trip arm.

2. An automatic railway crossing signal comprising a support, a signal arm slidably mounted thereon and means for moving the latter into operative or signalling position when the train reaches a predetermined distance from the crossing, said means comprising a trip arm adapted to be actuated by the engine, an actuating lever pivoted to the

support, a link between one end of the lever and the signal arm, a bar pivoted to the support and connected at one end with the actuating lever, a second similar bar connected with the trip arm, connections between said last mentioned arms and guide rollers for said flexible connections. 15

In testimony whereof he affixes his signature.

ADOLPH FRANZEN.
